UNITED STATES PATENT OFFICE.

FRED I. RAYMOND, OF EVANSTON, ILLINOIS, ASSIGNOR TO RAYMOND BROTHERS IMPACT PULVERIZER COMPANY, OF CHICAGO, ILLINOIS, A CORPORATION OF ILLINOIS.

PULVERIZING MILL.

Application filed June 25, 1923. Serial No. 647,582.

To all whom it may concern:

Be it known that I, FRED I. RAYMOND, a citizen of the United States, residing at Evanston, in the county of Cook and State of Illinois, have invented certain new and useful Improvements in Pulverizing Mills, of which the following is a specification.

My invention relates to a pulverizing mill from which the material when ground to sufficient fineness is removed by an air lift, and more particularly to mills of the type involving pendant rollers that are revolved at a high speed within and in contact with the inner surface of a grinding or bull ring between which and the rollers the material is reduced; and the primary object of the invention is to bring about a separation of the finely pulverized material from the larger particles and the removal of the same from the mill more effectively, rapidly and economically than has been possible heretofore, by providing the part of the mill in which the air is admitted with certain novel and improved constructions and arrangements for directing the air current against the material in a peculiarly advantageous manner.

The invention consists in the new and improved arrangements, devices and constructions, to be hereinafter described and claimed, for carrying out the above stated object and such other incidental objects as will be referred to in the following description of the preferred embodiment of the invention illustrated in the accompanying drawings.

In the drawings—

Fig. 1 is a vertical sectional view of a mill of the centrifugal type provided with the air lift arrangements of my present invention.

Fig. 2 is a sectional plan view on line 2—2 of Fig. 1, and

Fig. 3 is a view, in perspective, of the deflecting plate arranged in the lower part of the mill between the air intake and pulverizing means.

Referring to the drawings, 10 designates the casing of the mill having a base plate 11 shown as supported on a foundation 12. 13 designates a shaft extending vertically through the center of the casing 12 and provided at its lower end, outside of the cas-

ing, with a bevel gear 14 driven by bevel pinion 15 on driving shaft 16. The lower bearing of shaft 13 is indicated at 17. Suitable means is provided for supporting the upper part of the shaft but as the mounting of the shaft forms no part of my present invention the upper bearings are omitted for the sake of clearness. Pivoted at 18 to a spider 19 fixed to the upper end of shaft 13 are a plurality of roller journals 20 in which are revolvably supported the shafts 21 of pulverizing rollers 22, the latter being adapted to bear, through centrifugal force, against a grinding ring 23 fastened to an inwardly projecting rib 24 on the wall of the mill casing. The bottom plate of the mill, designated 25, is annular in form having a central opening 26 for admission of air to the mill from air intake duct 27. Arranged above opening 26 and between the same and the rollers 22 is a deflecting plate 28 secured to the under side of a spider 29 that is fixed to shaft 13. The deflecting plate is formed with a plurality of openings or circumferential notches 30 equal in number to the pulverizing rollers, through which openings project plows or scoops 32 fastened to downwardly extending, oblique webs 33 on the spider 29, the lower ends 34 of the plows working close to the annular bottom plate 25 and their upper ends 35 arranged so as to deliver the material scooped up from plate 25 into the spaces between the rollers and grinding ring in advance of the rollers. The diameter of the deflecting plate is substantially the same as the interior diameter of the grinding ring, or approximately so. The plate may be slightly larger as shown in the drawings.

The material may be fed into the mill in any desired manner. I have shown at the right hand side of Fig. 1 a rotary feeder 36 arranged in a feeding hopper 37. 38 designates the air outlet which will ordinarily be connected with some dust collecting device (not shown). Any suitable device may be employed for maintaining the circulation through the mill. The lower part of the mill casing is formed so as to provide an annular chamber 39 of larger diameter than the grinding ring and deflecting plate.

Operation.—Material fed into the mill by

feeder 36 falls downwardly through the mill and is carried around centrifugally by the rotation of rollers 22 and the structure on which they are supported. The material 5 is pulverized between rollers 22 and the grinding ring 23. Air is introduced into the bottom of the mill through duct 27 and air intake opening 26. The deflecting plate 28 which stands over opening 26 excludes 10 the air from the space at the center of the mill compelling it to pass first outwardly and then upwardly and inwardly in an annular stream which cuts obliquely through the stream of material falling from the 15 grinding ring. The finer particles are, in a large measure, picked up by this air current as the material falls and are carried off by the air current which finds its exit from the mill at 38. The remaining material, 20 including the heavier particles, which have not been sufficiently ground falls upon the deflecting plates 28, being carried inwardly by the air current even if the plate is of no greater diameter than the internal 25 diameter of the grinding ring. Little or none of it falls directly to the bottom of chamber 39. Of the material falling on plate 28 some of it spills over the edge of the plate and is subjected again to the separating 30 action of the air current, while the rest passes backwardly into the plow opening where it is also given a second air separation which carries the lighter particles out of the mill. The heavier particles in 35 the bottom of chamber 29 are scooped by the plows and, with the heavier particles falling on or carried into the plow openings, are delivered to the grinding ring in advance of the several rollers.

40 As a consequence of the arrangements described the finer ground material is removed from the region where the grinding takes place as soon as it has been sufficiently reduced. The two separations in the air 45 which the material receives before the heavier particles have fallen to the bottom of the mill, and the direction of the air current, which cuts across as well as upwardly through the stream of falling material, con- 50 duce to this result which adds to the efficiency of both grinding and separating operations by ridding the space in which these operations take place as completely as possible of the finer particles. The air current 55 acts on the material while suspended in the air, and in a very effective way, so that in comparison with other mills of this general type power may be economized through reduction of the strength of the air current drawn or forced through the apparatus. There is no chance of clogging 60 through accumulation of material since the plows are continually scooping up the material in chamber 39 through which it passes 65 to the grinding chamber. The air does not

enter the mill through a series of openings, as has been customary in mills of this general type, but through a single circular opening which cannot very well become clogged up, as is possible with a series of circumferentially arranged air openings, particularly inasmuch as, in the mill of the present invention, the air opening is continually freed of material by operation of the plows. With the old type of mill having a series of 70 air openings any material that may fall or be forced into the air openings is necessarily out of reach of the plows, whereas with the mill of this application the plows operate in a free open space between the central air 75 inlet and the space into which the heavier particles fall so that plows and air current act together to prevent any possibility of clogging.

Realizing that the principles of my invention might be utilized in machines different from that disclosed, I wish it to be understood that the invention is to be considered as covering all modifications within the scope of the appended claims. 80

I claim:

1. In a pulverizing mill, the combination with a circular grinding surface, grinding elements cooperating therewith, an air intake below said grinding surface, and means for feeding the material into the mill; of means for directing the incoming air outwardly and then upwardly and inwardly beneath the grinding surface and through the stream of material falling from said grinding surface to produce a separation of the material as it falls. 100

2. In a pulverizing mill, the combination with a circular grinding surface, grinding elements cooperating therewith, an air intake below said grinding surface, and means for feeding the material into the mill; of means for directing the incoming air outwardly and then upwardly and inwardly through the stream of material falling from said grinding surface to produce a separation of the material as it falls, and plows for scooping up the material collecting in the bottom of the mill and delivering it between said grinding elements and grinding surface. 110

3. In a pulverizing mill, the combination with a circular grinding surface, grinding elements cooperating therewith, an air intake below said grinding surface, and means for feeding the material into the mill; of means for excluding the incoming air from the center of the mill and directing it outwardly and then upwardly and inwardly beneath the grinding surface and through the stream of material falling from said grinding surface to produce a separation of the material as it falls. 120

4. In a pulverizing mill, the combination with a circular grinding surface, grinding elements cooperating therewith, an air intake 125

below said grinding surface, and means for feeding the material into the mill; of means for excluding the incoming air from the center of the mill and directing it outwardly 5 and then upwardly and inwardly through the stream of material falling from said grinding surface to produce a separation of the material as it falls, and plows for scooping up the material collecting in the bottom

10 of the mill and delivering it between the grinding elements and grinding surface.

5. In a pulverizing mill, the combination of a grinding ring, revolving pulverizing rollers which travel around and in contact 15 with the ring, an air intake below the rollers, means for feeding the material into the mill, and means for directing the incoming air in an annular current outwardly and then upwardly and inwardly beneath the ring and 20 through the material falling from said ring to produce a separation of the material as it falls.

6. In a pulverizing mill, the combination of a grinding ring, revolving pulverizing 25 rollers which travel around and in contact with the ring, an air intake below the rollers, means for feeding the material into the mill; means for directing the incoming air in an annular current outwardly and then 30 upwardly and inwardly through the material falling from said ring to produce a separation of the material as it falls therefrom, and means for scooping up the material in the bottom of the mill and delivering it between the rollers and ring.

7. In a pulverizing apparatus, a casing formed in the bottom with a central air intake, pulverizing means in said casing, and deflecting means arranged between the bottom 40 of the casing and the pulverizing means for directing the incoming air first outwardly and then upwardly and inwardly in an annular stream through the space adjacent the pulverizing means.

45. 8. In a pulverizing apparatus, a casing formed in the bottom with an air intake, pulverizing means in said casing, and deflecting means arranged between the bottom of the casing and the pulverizing means to 50 intercept material falling from said pulverizing means and to direct the incoming air outwardly beneath the pulverizing means, and other means to deflect this air upwardly and inwardly in an annular stream through 55 the space adjacent the pulverizing means.

9. In a pulverizing apparatus, a casing the bottom of which is formed with a centrally arranged air intake, pulverizing means in said casing, and a substantially horizontal 60 deflecting plate arranged between the pulverizing means and said air intake and in the path of material falling from said pulverizing means.

65. 10. In a pulverizing apparatus, a casing the bottom of which is formed with a cen-

trally arranged air intake, pulverizing means in said casing, a deflecting plate arranged between the pulverizing means and said air intake and in the path of material falling from said pulverizing means, and rotary 70 plows which scoop the material from the bottom of the mill outside of said opening and deliver the same to the pulverizing means.

11. In a pulverizing apparatus, a casing 75 the bottom of which is formed with a centrally arranged air intake, pulverizing means in said casing, a deflecting plate arranged below the pulverizing means and over said air intake, said plate being formed with 80 openings therein, and plows extending through said openings and arranged so as to scoop up the material from the bottom of the mill and deliver the same to the pulverizing means.

12. In a pulverizing apparatus, a casing the bottom of which is formed with a central air intake opening, pulverizing means in said casing, and a rotary deflecting plate arranged between said opening and pulverizing means to direct the air outwardly through the pulverized material, and provided with plows which scoop up the material in the bottom of the mill and deliver the same to the pulverizing means, and other means to deflect the air inwardly and upwardly between the plate and pulverizing means through the pulverized material.

13. In a pulverizing apparatus, the combination of a casing, the bottom of which is formed with an air intake opening, a grinding ring in said casing, a centrally arranged revoluble shaft, rollers carried by said shaft to bear, by centrifugal force, against the grinding ring, and a deflecting plate in the casing between said rollers and the intake opening the plate being of such diameter that the incoming air flowing therearound must pass first outwardly and then inwardly through the pulverized material falling from the pulverizing means.

14. In a pulverizing apparatus, the combination of a casing, the bottom of which is formed with an air intake opening, a grinding ring in said casing, a centrally arranged, revoluble shaft, rollers carried by said shaft to bear, by centrifugal force, against the grinding ring, and a deflecting plate on said shaft, the plate being of such diameter that the incoming air flowing therearound must pass first outwardly and then inwardly through the pulverized material falling from the pulverizing means.

15. In a pulverizing apparatus, the combination of a casing, the bottom of which is formed with an air intake opening, a grinding ring in said casing, a centrally arranged, revoluble shaft, rollers carried by said shaft to bear, by centrifugal force, against the grinding ring, a deflecting plate on said

shaft, said plate being formed with openings therein and plows extending through said openings.

16. In pulverizing apparatus, the combination of a casing the bottom of which is formed with a centrally arranged air intake opening, a grinding ring in said casing, a revoluble shaft centrally arranged in said casing, rollers supported on said shaft to bear by centrifugal force against the grinding ring, a deflecting plate secured to said shaft below the rollers and above said air intake openings, said plate being formed with circumferential recesses, and plows which are secured to said plate and extend upwardly in a diagonal direction through said recesses.

17. In a pulverizing apparatus, the combination of a casing formed with a circular grinding surface and with a chamber of larger diameter below said grinding surface provided with an air inlet, pulverizing elements cooperating with said grinding surface, and a deflecting plate arranged in said chamber and extending beneath the grinding surface and cooperating with the chamber walls to direct the inflowing air first outwardly and then upwardly and inwardly through the material falling from said grinding surface.

18. In a pulverizing apparatus, the combination of a casing formed with a circular grinding surface and with a chamber of larger diameter below said grinding surface provided with an air inlet, pulverizing elements cooperating with said grinding surface, and a revoluble deflecting plate arranged in said chamber and extending beneath the grinding surface and cooperating with the chamber walls to direct the inflowing air first outwardly and then upwardly and inwardly through the material falling from said grinding surface.

19. In a pulverizing apparatus, the combination of a casing formed with a circular grinding surface and with a chamber of larger diameter below said grinding surface provided with an air inlet, pulverizing elements cooperating with said grinding surface, and a deflecting plate of a diameter not substantially less than that of the grinding surface arranged in said chamber between the air inlet and grinding surface.

20. In a pulverizing apparatus, the combination of a casing formed with a circular grinding surface and with a chamber of

larger diameter below said grinding surface provided with an air inlet, pulverizing elements cooperating with said grinding surface, a deflecting plate arranged in said chamber and cooperating with the chamber walls to direct the inflowing air first outwardly and then upwardly and inwardly through the material falling from said grinding surface, and means carried by the deflecting plate for delivering the material in the bottom of the casing to said grinding surface.

21. In a pulverizing apparatus, the combination of a casing provided with means for pulverizing the material while in suspension in the air therein and formed with an air inlet in the bottom, and deflecting means arranged in the path of the material falling from the pulverizing means and in the path of the ingoing air, so that the air is directed first outwardly and then inwardly beneath the pulverizing means and through the falling material, which is subjected to successive air separations while suspended.

22. In a pulverizing apparatus, the combination of a casing provided with means for pulverizing the material while in suspension in the air therein and formed with an air inlet in the bottom, deflecting means arranged in the path of the material falling from the pulverizing means and in the path of the ingoing air, so that the air is directed first outwardly and then inwardly through the falling material, which is subjected to successive air separations while suspended, and means for returning the heavier particles to the pulverizing means.

23. In a pulverizing apparatus, the combination with a casing, grinding elements in the casing, and means for delivering air into the casing, of means within the casing for causing the incoming air to pass successively back and forth beneath the grinding elements and through the pulverized material falling therefrom.

24. In a pulverizing apparatus, the combination with a casing, grinding elements in the casing, an air inlet in the bottom of the casing, and means for delivering air therethrough, of means within the casing for causing the incoming air to pass successively back and forth beneath the grinding elements and through the pulverized material falling therefrom.

FRED I. RAYMOND.
